UNITED STATES PATENT OFFICE.

JOHN THEODORE URBACH, OF WESTON, WEST VIRGINIA, ASSIGNOR OF
ONE-HALF TO HARRY W. LIGHTBURN, OF SAME PLACE.

CHURN.

SPECIFICATION forming part of Letters Patent No. 496,674, dated May 2, 1893.

Application filed February 8, 1893. Serial No. 461,240. (No model.)

To all whom it may concern:

Be it known that I, JOHN THEODORE URBACH, a citizen of the United States, residing at Weston, in the county of Lewis and State of 5 West Virginia, have invented certain new and useful Improvements in Churns; and I do hereby declare the following to be a full, clear, and exact description of the invention, such as will enable others skilled in the art to which 10 it appertains to make and use the same.

This invention has relation to improvements in churning and it consists in the construction and novel combination of parts all as will be hereinafter more fully explained and more particularly pointed out in the appended claims. 15

The annexed drawings to which reference is made, fully illustrates my invention, in which—

Figure 1, represents a vertical sectional view 20 of my improved churn. Fig. 2, is an enlarged detail view of the vertical bars, taken on transverse line *x*, *x*, Fig. 1. Fig. 3 is a detail view showing the rack and bar "B," and Fig. 4 is a face view, in detail of the stationary bar.

Referring by letter to the accompanying 25 drawings A, designates the churn body, having the lid or cover *a* provided with the usual central perforation, through which the dasher rods pass.

30 B, B', indicate two vertical rods which slide one upon the other; the rod B, is fixed or stationary to the churn body and adjustable by means of the bracket *b*, hereinafter explained. This rod B, extends from the bottom of the 35 churn, as at *c* upwardly and is bent at its upper end, the downwardly projecting end *d* serving as a bearing for the shafts *e* and *f*, and said bent portion serves as a handle for lifting the dashers and rods from the churn body.

40 *e* represents a shaft which has its bearing in the rod B; the outer end of which is provided with a gear wheel *g* having a handle *h* and *f* indicates a crank shaft; one end of which is provided with a fly wheel *i*, and the opposite 45 end thereof has secured to it a pinion *j* which engages the gear wheel *g* aforesaid. Connected to the crank of this shaft *f* is a pitman K, the lower end thereof is pivoted to the upper end of the vertically movable bar B', as at *l*.

50 On top of the cover of the churn body is secured a bracket *b*, the vertical portion of which

partly surrounds the two rods, as shown in dotted lines as at *m* while the lower portion, grasps the rod B, and by means of the thumb screw *n*, which is screwed up, binds or secures 55 said rod to the bracket and holds the same firmly in place. The lower end of the movable rod is bent at right angles and flattened as at *o*, forming a dasher, having perforations and said rod is provided with a rack or teeth *p* on 60 its inner face, which engage a pinion *q*, seated in bearing *r* in the stationary rod B. This pinion is arranged on a shaft, having its bearing in said rod, is provided with two dasher blades *s*, *s*, which are preferably perforated 65 and a loop *t*, on the rod B, and surrounding the rod B' serves to keep the two rods in close relation to one another. Thus it will be seen from the above description, that the dasher, rods and operating mechanism can be readily 70 adjusted to different sized churn bodies, simply by the operator loosening the thumb screw and adjusting the rods thereto when the thumb screw is again tightened, thereby holding said rod B in a fixed position and the extended ends of the bracket as shown in dotted lines serve to guide and hold the movable bar or rod in place in its up and down movement. It will be further observed that when the operator turns the crank handle, motion is given to 75 the crank shaft through the medium of the pinion meshing with the gear wheel, and through the medium of the pitman the movable rod is given a vertical sliding movement, and by means of the rack thereon, causing the pinion 80 to revolve, first in one direction, in its upward movement and in a reverse direction in its downward movement, thereby causing the dasher blades to revolve first in one direction and again in the opposite direction, at the 85 same time, the lower blade on the end of the movable bar has an up and down motion, and is agitating the cream in the body and assisting the two revolving blades, in churning, and a churn as herein described is easily taken 90 apart for cleaning, can be adjusted to different sized churning, and is durable, easily operated and at the same time cheap to manufacture. 95

Having thus described my invention, what 100 I claim as new, and desire to secure by Letters Patent, is—

1. In combination with the churn body of the stationary and movable rods, the stationary rod held in the churn by means of the bracket *b*, the upper end of said rod being bent 5 to form a loop and adapted to form bearings for the operating mechanism, the bracket *b* secured to the churn cover, the rack and pinion, the blades on the shaft of said pinion and the lower dasher bent at right angles to the movable rod and formed integral therewith substantially as described.
- 10 2. The combination with the stationary rod having the gear or pinion and blades on its shaft and operating mechanism described of the movable bar having the teeth or rack and a dasher blade at its lower end, bent at right 15 angles and formed integral therewith, substantially as described.

3. The combination of the bars *B*, *B'*, constructed as described the operating mechanism therefor the angular bracket having the thumbscrew and the gripping flanges and secured to the churn cover, the rack and pinion, the blades on the shaft of said pinion and the lower dasher bent at right angles to the movable rod and formed integral therewith substantially as described. 20 25

In testimony whereof I affix my signature in presence of two witnesses.

JOHN THEODORE URBACH.
